**COMBINED LICENSE PLATE ILLUMINATOR,
REAR LAMP AND REFLECTOR FOR AUTO-
MOTIVE VEHICLES**

John B. Dickson, Kew Gardens, N.Y., assignor to Signal-
Stat Corporation, Brooklyn, N.Y., a corporation of
New York

Filed Apr. 4, 1960, Ser. No. 60,024

Term of patent 7 years

(Cl. D48—32)

FIG. 1

FIG. 2

FIG. 3

FIG. 4

FIG. 1 is a top plan view of a combined license plate illuminator, combination rear lamp, and reflector for automotive vehicles embodying my new design;

FIG. 2 is a side elevational view thereof;

FIG. 3 is a bottom plan view thereof; and

FIG. 4 is an end elevational view thereof.

The side of the combined license plate illuminator, combination rear lamp, and reflector, not shown being substantially plain.

I claim:

The ornamental design for a combined license plate illuminator, rear lamp and reflector for automotive vehicles as shown and described.
